ACTUATING MECHANISMS

Taft E. Armandroff, New Britain, Conn., assignor to
General Electric Company, a corporation of New York
Filed Sept. 18, 1961, Ser. No. 138,861
5 Claims. (Cl. 74—503)

This invention relates to actuating mechanisms and has particular relation to a mechanism mounted on a panel for actuating electrical devices located on one side of the panel by an operation performed at the other side of the panel.

Various means have heretofore been proposed for effecting actuation of electrical devices at one side of a panel by an operation performed at the other side of the panel. Previous designs of such actuating mechanisms either have not been reliable, have been relatively expensive, have possessed substantial front to rear dimensions, or have incorporated a large number of parts. Furthermore, many prior actuating mechanisms of this type include metallic parts so arranged as to present the possibility of electrical shock to operating personnel.

It is accordingly a primary object of the invention to provide an improved actuating mechanism of small, reliable and inexpensive construction for actuating electrical devices on one side of a panel by an operation performed on the other side of the panel.

It is another object of the invention to provide an actuating mechanism of the type above-described including a minimum number of parts so arranged as to eliminate the possibility of electrical shock to operating personnel, and to permit rapid assembly and disassembly thereof.

It is a further object of the invention to provide an actuating mechanism of the type above-described which is of rugged construction and which has a small front to rear dimension.

In carrying out the invention in one preferred form an actuating mechanism is associated with a fixed panel and comprises a movable device having at one side of the panel an insulating actuatable part and having at the other side of the panel an insulating operating part including a pair of insulated arms to be moved with the actuatable part to actuate a pair of electrical devices positioned on such other side of the panel. The panel includes an opening toward which the actuatable part is to be depressed to effect movement of the operating part. The panel carries a support located on the side of the panel containing the operating part, and a pair of conical spiral springs engage the support and the movable device so as to bias the actuatable part away from the panel. The springs compress within themselves when the device is actuated and therefore do not add appreciably to the front to rear dimension of the device.

Other objects and advantages of the invention will become apparent from the following description taken in conjunction with the accompanying drawings in which:

FIG. 1 is a view in front elevation showing a panel with parts broken away and the actuatable part of the actuating mechanism at the front side of the panel;

FIG. 2 is a view in section taken along the line 2—2 of FIG. 1; and

FIG. 3 is a view similar to FIG. 2 showing the device in an actuated condition.

Referring now to the drawings there is illustrated in

2

FIG. 1 a portion of a panel 10 adapted to operatively support the actuating mechanism of the present invention. The panel 10 may comprise a wall of a control unit or other apparatus which contains one or more electrical devices to be actuated by means of the actuating mechanism. The panel 10 includes an opening 11 of generally rectangular configuration communicating with the inner side of the panel at which the devices to be actuated are located.

10 The actuating mechanism of the present invention preferably includes a pair of movable members formed of suitable insulating material which are movable relative to the panel 10 comprising an actuatable member 12 located at the outer side of the panel 10 toward the observer as viewed in FIG. 1 to be actuated by an operator, and an operating member 13 connected to the part 12 and located at the inner side of the panel 10. The devices to be actuated are designated generally by the numerals 14 and, as shown in FIG. 2, two spaced devices 14 are located at the inner side of the panel 10 to be actuated by spaced laterally extending arms 15 which may be formed of a metallic material and which are carried at opposite ends of the member 13, and detachably secured to the member 13 by screws 16 extending through elongated openings 17 of the member 13. The devices 14 may assume various forms, such as motor starters, containing operating elements, such as overload reset buttons 18, adapted to be reciprocated in vertical directions as viewed in FIG. 2 in response to vertical movements of the arms 15 on the member 13.

20 The mechanism of the present invention eliminates the possibility of electrical shock to operating personnel. To this end the arms 15 are insulated from each other by the insulating material of the member 13. In addition, the metallic screws 16 which engage the arms 15 are recessed within the openings 17 so as to be spaced from the panel 10 when the mechanism is in its normal position of FIG. 2.

30 As best shown in FIG. 2 the members 12 and 13 are operatively connected for movement as a unit by means of a fastener shown in the form of a screw 20 extending through an elongated aperture 21 in the member 13 into threaded engagement with a threaded opening 22 in the member 12. With such arrangement, the members 12 and 13 are movable as a unit in vertical directions as viewed in FIG. 2 in response to depression and release of the member 12 by an operator located at the outer side of the panel 10. When the members 12 and 13 are secured together, a projection 23 of the member 12 fits within a slot (not shown) of the member 13 to engage the base of the slot (not shown).

40 In order to provide an operative connection between the panel 10 and the actuating mechanism the panel 10 is provided with a support for engaging resilient means which also engages the actuating mechanism as will presently appear. As shown in FIG. 2 the support comprises a pair of generally L-shaped fingers 24 preferably lanced out of the material of the panel to be located at the inner side of the panel. The fingers 24 include generally parallel parts 25 extending substantially perpendicular to the plane of the panel and connected to the panel, and parallel generally coplanar parts 26 connected to the parts 25 and extending parallel to and spaced from the plane of the panel.

50 When the actuating mechanism is operatively associated with the panel 10, the fingers 24 are positioned with-

in spaced cavities 27 formed in the member 13 with the parts 26 of the fingers located adjacent the bases of the cavities 27 when the actuating mechanism is in a non-actuated condition as shown in FIG. 2. The cavities 27 are spaced by a projection 28 containing the aperture 21 and also containing the slot (not shown) within which the projection 23 of member 12 is positioned.

The resilient means previously referred to for operatively connecting the actuating mechanism and the panel is preferably in the form of a pair of conical spiral springs 30 positioned intermediate the fingers 24 and the member 12 with the larger convolutions of the springs engaging the parts 26 of the fingers 24 and with the smaller convolutions engaging the bases of a pair of spaced pockets or recesses 31 formed in the member 12. The springs 30 are normally in expanded conditions when the actuating mechanism is non-actuated to bias the member 12 to its full extent away from the panel at the outer side thereof. For this condition the member 13 engages the inner surface of the panel 10 as shown in FIG. 2.

In order to actuate the actuating mechanism for effecting vertical movement of the operating elements 18 as viewed in FIG. 2, the member 12 is depressed to effect movement thereof upwardly as viewed in FIG. 2 to the position shown in FIG. 3. Such movement of the member 12 is readily performed by an operator located at the outer side of the panel 10 or below the panel as viewed in FIGS. 2 and 3. When the member 12 is depressed, the member 13 is moved therewith and the springs 30 are compressed within themselves due to their conical configuration as shown in FIG. 3. Upward movement of the member 13 as viewed in FIG. 3 results in the arms 15 contacting the elements 18 to effect corresponding upward movement thereof to effect actuation of the devices 14. When the member 12 is released after actuation thereof to the position shown in FIG. 3, the springs 30 are expanded to effect downward movement of the member 12 and the member 13 from the positions shown in FIG. 3 to the normal positions illustrated in FIG. 2. Such downward movement is terminated by engagement of the member 13 with the panel 10.

It is noted that when the member 12 is depressed to its full extent, the springs 30, due to their conical configurations, are compressed within themselves such that the thickness of but a single convolution of each spring 30 lies between the finger parts 26 and the upper surface of the member 12 as viewed in FIG. 3. Therefore, the springs 30 do not add appreciably to the front to rear dimension of the mechanism thereby minimizing such dimension.

It can be appreciated that the arms 15 may assume various forms. For example, the arms 15, rather than being detachably connected to the member 13, may comprise integral parts of the member 13 and, for example, may be molded therewith from a suitable insulating material. The arms 15 may assume various configurations and lengths so as to be capable of actuating elements 18 which are spaced by distances different than those shown. It is also understood that the arms 15 may be omitted if desired and the rear surface of the member 13 employed to effect movement of the elements 18. The members 12 and 13 are configured so as to have substantial clearance from parts of the panel 10 such that the actuating mechanism will not jam against the panel 10 when actuating pressure is applied to the member 12 off-center thereof. It is also noted that a single fastener in the form of the screw 21 is utilized to operatively connect the members 12 and 13.

While I have shown and described a particular embodiment of my invention, it will be obvious to those skilled in the art that various changes and modifications may be made without departing from my invention in its broader aspects and I, therefore, intend in the appended claims to cover all such changes and modifica-

tions as fall within the true spirit and scope of my invention.

What I claim as new and desire to secure by Letters Patent of the United States is:

1. An actuating mechanism comprising, a panel having an opening, an actuatable member on one side of said panel to be depressed toward said opening, an operating member on the other side of said panel secured to said actuatable member, said actuatable member having a pair of spaced recesses each opening at said panel opening, said operating member having a pair of spaced cavities each opening at said panel opening, a pair of spaced generally L-shaped fingers struck out from the panel at said other side thereof positioned within the cavities of said operating member, said fingers having generally coplanar parts parallel to and spaced from said panel and adjacent the bases of said cavities, and a pair of conical spiral springs seated in the recesses of said actuatable member in engagement with said parts of said fingers to normally bias the actuatable member away from the panel, said springs being compressed within themselves when said actuatable member is actuated.

2. An actuating mechanism comprising, a metallic panel having an opening, an insulating actuatable member on one side of said panel to be depressed toward said opening, an insulating operating member on the other side of said panel, said actuatable member having a threaded hole and a pair of spaced recesses each opening at said panel opening, said operating member having a pair of spaced cavities and an aperture extending entirely through the operating member with the cavities and aperture each opening at said panel opening, a screw extending through said aperture into said threaded hole to secure the members together for movement as a unit, a pair of spaced generally L-shaped fingers struck out from the panel at said other side thereof positioned within the cavities of said operating member, said fingers having generally coplanar parts extending toward each other parallel to and spaced from said panel and adjacent the bases of said cavities, a pair of conical spiral springs seated in the recesses of said actuatable member in engagement with said parts of said fingers to normally bias the actuatable member away from the panel and the operating member into engagement with the panel, and laterally extending metallic arms spaced on said operating member for engagement with devices located at said other side of the panel; said springs being compressed within themselves when the actuatable member is actuated.

3. An actuating mechanism comprising, a metallic panel having an opening, an insulating actuatable member on one side of said panel to be depressed toward said opening, an insulating operating member on the other side of said panel, said actuatable member having a threaded hole and a pair of spaced recesses each opening at said panel opening, said operating member having a pair of spaced cavities and an aperture extending entirely through the operating member with the cavities and aperture each opening at said panel opening, a screw extending through said aperture into said threaded hole to secure the members together for movement as a unit, a pair of spaced generally L-shaped fingers struck out from the panel at said other side thereof positioned within the cavities of said operating member, said fingers having generally coplanar parts extending toward each other parallel to and spaced from said panel and adjacent the bases of said cavities, a pair of conical spiral springs seated in the recesses of said actuatable member in engagement with said parts of said fingers to normally bias the actuatable member away from the panel and the operating member into engagement with the panel, laterally extending metallic arms spaced on said operating member for engagement with devices located at said other side of the panel; said springs being compressed within themselves when the actuatable member is actuated, said operating member having a pair of spaced openings extend-

ing therethrough, and a pair of screws recessed in said openings and extending into threaded openings of said arms to secure the arms to said operating member, said screws being spaced from said panel when the mechanism is in a normal condition and the operating member engages the panel.
